J. WALDHEIM

APPARATUS FOR HOLDING WORK WEBS FOR TYPEWRITING MACHINES

Filed June 14, 1922

UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

APPARATUS FOR HOLDING WORK WEBS FOR TYPEWRITING MACHINES.

Application filed June 14, 1922. Serial No. 568,093.

The present invention relates to an improved apparatus for holding a web or work-sheet to be used in connection with continuous billing typewriting machines, one form 5 of which is shown in the patent to Wernery & Smith, No. 1,132,055, granted March 16, 1915.

In a machine of this type, work-sheets or webs are used in several layers or plies, each 10 provided with printed forms constituting one piece of work, which, when completed, may be torn from the continuous web. Carbon-sheets interleaved between the webs or plies are mounted on a carbon-carriage, so 15 as to advance with the web toward the platen while typewriting, and so as to be drawn back by the carbon-carriage into the succeeding form-section of the web after the leading form-section has been typed, and prior 20 to detachment from the web of such leading form-section.

To save time and trouble in substituting a work-web of one style for that of another, the carbon-sheets, as shown in United States 25 Letters Patent to Fortin, No. 1,237,319, granted August 21, 1917, are not directly attached to the carbon-carriage in the machine, but are attached to a plate or holder which is detachably secured to the carbon-carriage 30 so that a carbon-sheet-holding plate for any set of webs, with the carbon-sheets interleaved therewith, may be removed as a unit from the carbon-carriage, and another carbon-sheet-holding plate, with carbon-sheets 35 already interleaved with the plies of the desired set of webs, substituted therefor. Containers or cabinets for the several webs and their respective carbon-sheet-holding plates and interleaved carbon-sheets have heretofore been devised to provide for a feed of the 40 web from its container to the carbon-carriage of the type-writing machine, when the sheet-holder shall have been placed on the latter.

The present invention has particular reference to an equipment which comprises the above-mentioned continuous billing apparatus as applied to a bookkeeping typewriting machine; and which involves a support, other than the machine-frame itself, for the 45 carbon-carrier table, in order to allow clearance for, and access to, certain attachments commonly present on the rear of bookkeeping machines. Such other support for the carbon-carrier-table in turn involves means 50 for determining a fixed relation of the same

to the machine, so that the carbon-carrier-table may properly connect to the platen-carriage of the machine, and may move with the latter in letter-feed and return directions without binding. Because of the size of 60 bookkeeping machines, a special stand therefor, easily rolled from place to place, is commonly employed; and, by providing the stand with centering means for the machine and for the auxiliary carbon-carrier table-support, the correct relations of these may be 65 assured. It will be understood, however, that the invention is not confined to use in connection with a bookkeeping machine or with a machine-stand of any special type. 70

An object of the invention is the provision of a combined holder or support for a table over which continuous webs or work-sheets may be fed to the platen, and means for supporting the work-web holder apparatus from 75 the typewriting-machine stand, clear of the floor, and independently of the machine itself; and of means whereby the work-web holder apparatus is adjustable upon such combined table and work-web holder apparatus supporting device to permit any desired web in the work-web holder apparatus to be brought to set position with respect to the work-sheet table.

A feature of the invention is a novel and 85 simple arrangement of runways, on the combined support, for so carrying the work-web holder apparatus that the same may be slidably moved thereon to any selected position, or, if desired, may be removed entirely as 90 part of the equipment, or be interchanged with other work-web holder apparatus containing different webs.

Other features and advantages will herein-after appear. 95

In the accompanying drawings,

Figure 1 is a view in side elevation, partly cross-sectional, showing an Underwood bookkeeping machine, with continuous billing attachment and stand therefor, and with the combined work-box holder apparatus and carbon-carrier table-support of the present invention connected to the stand. 100

Figure 2 is a view in rear elevation of the work-box holder apparatus and carbon-carrier table-support shown in Figure 1. 105

Figure 3 is a detail view, in side elevation, of the latch for holding the work-box holder apparatus in selected position.

The frame 10 of the bookkeeping machine 110

is shown supported on a platform 11 of a stand having uprights 12 and cross-braces 13, and having the feet 14 thereof provided with rollers 15, to permit the stand with the machine and associated parts to be wheeled from place to place.

The platen 16 is revolvably mounted on an axle 17, carried by arms (not shown) forming part of a swinging frame pivoted at 19 to the carriage-frame 20. The normal position of the platen is its full-line, Figure 1 position, but it may be swung up around the axis 19 as a pivot to permit the fan-fold webs to be advanced in the usual manner, for detachment of the leading written section and for placement of the succeeding section thereof. The usual front and rear pressure-rolls 21 and 22 are provided for feeding the web with the platen. The carriage runs on a rod 23 carried by the main frame.

Attached to the carriage are brackets 24 for supporting the forward end of the carbon-carrier-table 25. The brackets 24 are connected by a cross-piece 26, having other brackets or ears 27 thereon; and the ears 27 carry the bar 28 which defines the front of the table 25. On the table 25 is a carbon-holder and carrier 29, adapted to move with the carbons (not shown) and with the web 30 toward the platen as the carbons and web have their line-feed movements around the platen, and which is adapted to be moved backward with the carbons, independently of the web, to draw the carbons into a succeeding web-section after the leading web-section has passed around the platen. It is unnecessary here to describe in detail the entire construction of the table and associated parts, reference being made to the aforesaid United States Letters Patent to Fortin, No. 1,237,319, for such description thereof as may be desired. Suffice here to say that the carbon-holder of the Fortin patent comprises a plate 31, having secured thereto a number of clips (not shown), each of which clips engages and holds the rear end of a carbon-sheet, the several clips being stepped up, one from another, more conveniently to enter and slide between the superposed web-plies.

In the Fortin patent, a single fan-fold web is shown; the superposed plies forming the web each being composed of detachable units bearing the same individual form or blank. Instead of the single web comprised of fan-folded superposed sheets or strips, several single strips or webs, as here indicated at 32 above the platen, may be employed; each of the superposed webs being composed of such detachable units.

The table 25, near the rear thereof, has a pair of depending brackets 34, each of which carries a roller 35 which rides on a rail 36, supported on brackets 37. The brackets 37 thus support the rear of the carbon-carrier-

table, and the latter, by reason of the rolls 35 riding on the rail 36, is free to have letter-feed and return movements with the platen-carriage of the typewriting machine, to which it is connected at its forward end. 70

The right and left hand brackets 37 are connected at the rear by rails 36 and 38, and at the front by a bar 39 carried by arms 40 secured by screws 41 to the brackets. The bar 39 serves as a front support for the 75 brackets 37 on the platform of the stand 11, and is secured to the platform of the stand by screws 42. Each of the brackets 37 has also a front vertical reach 43, the lower end of which is turned outward laterally, as 80 shown at 44 in Figure 2, and is turned in the shape of a U around the corresponding rear upright 12 of the machine-stand 11. By means of screws 45, the U-shaped offsets 44 of the brackets 37 are fixed to the uprights 85 12 of the machine-stand.

In assembling the brackets 37 on the stand 11, the bar 39 is first positioned and screwed in place. The brackets 37 are then separately brought to position against the outside faces of the arms 40 of the bar 39, with their U-shaped extensions 44 embracing the legs 12 of the stand. The screws 41 are then applied to secure the brackets to the bar 39. The rear rails 36 and 38 are then set in place on the brackets 37. Thereupon the set-screws 45 are tightened to fix the lower front portions of the brackets 37 to the legs of the stand. The setting of the bar 39 by the screws 42 determines the proper setting of the rail 36, so that the latter may be parallel to the path of movement of the carriage on the machine-frame. 100

The brackets 37 include arms 46, which are secured thereto by screws 47, and which extend downward and rearward, with an outward flare, indicated in Figure 2, from the foot of the uprights 43 to the rail or bar 38. The bar 38 has secured thereto ears 48, which support and hold a rail 49, extending lengthwise of the stand. At the upper ends of the brackets 37, other brackets or ears 50 are held by means of screws 51. The ears 50 support and hold a rail 52, extending lengthwise of the stand, parallel to the rail 49. 110

The rails 49 and 52 serve as runways, on which the work-web holder apparatus is supported for adjustment laterally, with respect to the carbon-carrier-table 25, to permit different tiers of web-holders to be selectively positioned for use of the desired web. The frame of the work-web holder apparatus or standard comprises four bars or uprights 53, having offset ends. The offsets 54 at the lower ends of the bars 53 are connected by a tie or cross piece 55. Secured to the cross-piece 55 are ears 56, on each of which is mounted a roller 57, grooved to ride on the rail 49. At their upper ends the bars 53 are 125 130

first offset forward, as indicated at 58 in Figure 1, and at the forward ends of the offsets 58 are lateral offsets 59, on which is secured a tie or cross-piece 60. On the 5 cross-piece 60 are a pair of rollers 61, which are held by the weight of the work-web holder apparatus, against the forward face of the rail 52, so as to ride thereon. A pair of guards 62, secured to the cross-piece 60, 10 extend around behind the rail 52, to prevent forward displacement of the upper end of the work-web holder apparatus.

In Figure 2, two banks or tiers 63, 64 of web-plies are shown. The bank of web-plies 15 63 is shown as comprising four web-plies 65, 66, 67 and 68, which are superposed and are led from supply-rolls 69, 70, 71 and 72, respectively, to the carbon-holder 29 on the carbon-carrier-table, and as also comprising 20 three other web-plies 73, 74 and 75, which are superposed and led from supply-rolls 76, 77 and 78 to the carbon-holder on the table, where they are superposed on the web-plies 65, 66, 67 and 68, to form a web in seven 25 layers, between which carbon-sheets are interleaved at the carbon-holder, the whole being then led to the platen, for the printing operation. The bank of webs 64 also has seven web-plies led from rolls to a carbon-holder 29 in the same manner as the web-plies which form the bank 63. It will be understood that the forms on these latter web-plies may be different from the forms on the web-plies of the bank 63, and the bank 30 35 40 45 50 55 60 65 70 75 80 85 90 95 100 105 110 115 120 125 130

64 may be substituted, at will, for the bank 63 by interchanging the carbon-holders 29 and 29^a, as above noted. The carbon-holder not in use, with the web-plies secured thereto, may, as shown in Figure 1, be held in a trough 79, carried on arms 80, projecting rearward from the cabinet-standards 53, below the lower rear supply-rolls. In effecting the interchange, the work-web holder apparatus is slid on the rails 49 and 52, to move one bank of web-holders out of center position, with respect to the carbon-carrier-table, and to move the other bank into such center position.

To hold the work-web holder apparatus in proper position on the rails 49 and 52, for use of the selected bank of web-plies, a lock is provided. This lock, as shown in Figure 3, comprises a dog 87, pivoted at 88 to the offset 58, at the upper end of the left-hand (Figure 2) standard 53. The rail 52 has two notches 89 and 90 therein, to receive the nose 91 of the dog. In Figures 2 and 3, in which the work-web holder apparatus is positioned for use of the left-hand Figure 2 bank of plies, the dog 87 is in engagement with the notch 89. When, however, the work-web holder apparatus is moved to the left, for use of the right-hand bank of web-plies, the dog 87 comes into registration with the notch 90 at the left-hand (Figure 2) end

of the rail 52. A leaf-spring 92 causes the dog automatically to enter the desired notch when the dog comes into registration with such notch, upon sufficient movement of the work-web holder apparatus in one or the other direction; and the spring 92 serves to hold the dog in the selected notch against accidental displacement. The work-web holder apparatus is unlocked from the rail 52 by means of a finger-piece 93 on the dog. 75

One of the multi-ply-webs is shown at 81 as led over a rod 82 at the rear of the table 25, thence forward over the table 25 and over a rod 83, carried by brackets 24 at the rear of the platen. From the rod 83 the web 80 is led downward, around the platen, and thence upward across a table 84 on the platen-carriage. In order that the forward web-section may feed freely with the platen, unresisted by the supply-rolls, a slack is provided in the web at 85, between rollers 96 at the top of the work-web holder apparatus, and rail 82 on the table; this slack being effected by a forward and then a rearward movement of the carbon-holder, after the leading web-section has been typed and before typing of the next web-section. For gripping the web-plies, to draw off from the rolls a length of web sufficient to form the slack 85, a clamp 86, which may be of well-known form, is provided on the carbon-holder 29. After the slack 85 has been formed, the clamp 86 is released, so as to be ineffective when movement of the carbons, relative to the web-plies, is desired. 100

It will be noted that, by reason of the mounting of the work-web holder apparatus on the brackets 37, the work-web holder apparatus is movable as a unit with the type-writer-stand from place to place. The work-web holder apparatus is, however, readily detachable from the brackets 37 when not desired, or when another work-web holder apparatus is to be substituted therefor, by movement of the work-web holder apparatus off of the ends of the rails 49 and 52. Collars or stops 94 and 95 on the rail 49 prevent accidental throw of the work-web holder apparatus to a position where its supporting rolls will leave the rails. These collars or stops may also serve to assist the dog 87 in finding its desired notch 89 or 90. For instance, when the work-web holder apparatus is thrown to the stop 94, the dog may register with the notch 90, and, when the work-web holder apparatus is thrown to the stop 95, the dog may register with the notch 89. To place or remove a work-web holder apparatus, it is simply necessary to remove one of the collars 94 and 95. 115 120 125

It will also be noted that, in supporting the carbon-carrier-table on the brackets 37, instead of on the machine-frame, and in so shaping the brackets 37 to provide considerable clearance between the same and the 130

machine-frame, ample space is allowed for the attachments (not shown), but usually present on the rear of the bookkeeping machine, and ample provision is made for easy 5 access to such attachments.

Variations may be resorted to within the scope of the invention, and portions of the improvements may be used without others.

Having thus described my invention, I 10 claim:

- 11 1. The combination with a stand adapted to support a typewriting machine of carbon-carrier type, of brackets mounted on the stand, a movable rack including a plurality 15 of supports and work-sheet-holder rolls arranged in banks in said supports, runways on the brackets supporting the rack whereby the rack may be moved to bring the holder rolls into operative position, rear- 20 wardly-extended arms supported on said supports of the rack, and a trough supported on said arms adapted to receive a carbon-carrier usable with the holder rolls.
- 21 2. The combination with a stand for sup- 25 porting a typewriting machine, of brackets mounted on the stand having upper and lower runways without the limits of the

stand, a movable rack leaning outwardly on its base and including work-sheet holder rolls journaled in the rack, an arm extended 30 from the top of the rack to the upper runway connecting the top of the rack to the upper runway, and means on the base of the rack supporting the latter on the lower runway, whereby the rack may be moved to 35 bring the holder rolls into operative position.

3. The combination of a stand for a type-writing machine, brackets having vertical reaches secured to the stand and arms ex- 40 tended from the tops and bottoms of the reaches upwardly and downwardly, horizontal rails laid across the ends of the arms, a work-web-holder apparatus including up- right bars and horizontal rollers, a cross- 45 piece joining the lower ends of the up- rights together, rollers mounted on the cross- piece and running on the lower rails, arms extended forwardly from the tops of the up- rights, a cross-piece joining the forward 50 ends of the arms together, and rollers se- cured to the cross-piece and riding on the forward face of the upper rail.

JOHN WALDHEIM.
